PACKAGING DISPLAY TRAY

Richard F. Reifers, New Canaan, Conn., assignor to
Diamond International Corporation, New York, N.Y.

Filed Dec. 17, 1970, Ser. No. 26,551

Term of patent 14 years

Int. Cl. D9—03

U.S. Cl. D9—243

FIG. 1.

FIG. 2.

FIG. 3.

FIG. 4.

FIG. 6.

FIG. 5.

FIG. 8.

FIG. 9.

FIG. 10.

FIG. 11.

FIG. 1 is a top perspective view of a packaging display tray showing my new design;

FIG. 2 is a plan view of the tray shown in FIG. 1;

FIG. 3 is a side elevation view of the tray shown in FIG. 1;

FIG. 4 is a sectional view taken along line 4—4 of the tray shown in FIG. 3;

FIG. 5 is an end elevation view of the tray shown in FIG. 1;

FIG. 6 is a bottom view of the tray shown in FIG. 1;

FIG. 7 is a top perspective view of a modified form of the design of FIG. 1 wherein the side walls have a flange extending outwardly therefrom;

FIG. 8 is a plan view of the tray shown in FIG. 7;

FIG. 9 is a side elevation view of the tray shown in FIG. 7;

FIG. 10 is a sectional view taken along line 10—10 of the tray shown in FIG. 9;

FIG. 11 is an end elevation view of the tray shown in FIG. 7; and

FIG. 12 is a bottom view of the tray shown in FIG. 7.

I claim:

The ornamental design for a packaging display tray, as shown and described.
